CONTROL HEAD FOR INDICATORS

Bradford B. Holmes, Stonington, Conn., assignor
to Ruth V. Holmes, Stonington, Conn.

Application November 4, 1932, Serial No. 641,275

11 Claims. (Cl. 33—204)

This invention relates to control heads for compasses and other indicating devices, and particularly to heads adapted for use with compasses forming parts of automatic steering systems for dirigible craft, including marine, aerial and land vehicles.

The invention disclosed herein constitutes an improvement upon the structure disclosed and claimed in my copending application Serial No.

10 374,098, filed June 27, 1929, now Patent 1,939,775, December 19, 1933, reissued as No. 19,338, October 9, 1934; as well as that of Serial No. 412,418, filed December 7, 1929, now Patent No. 1,993,548, March 5, 1935.

15 In these applications, disclosure was made of different types of control heads rotatably secured to a compass or other indicating instrument, but the heads were not closed at the bottom against the entry of dirt and moisture, nor could they be removed without disarranging

20 the contact mechanism. Furthermore, in the cases referred to, the armature of the control head was secured to the contact arm, thereby increasing its mass and inertia and preventing relative rotation between the two. Also, the di-

25 ameter of the spindle was so small that a substantial armature bearing could not be provided. By enclosing the control head in a dust and moisture tight casing, and refining the structural arrangement of the contact arm lifting mechanism, accuracy of control and quickness of response have been tremendously improved.

30 One object of the invention is, therefore, to provide a control head which is removable at will from the compass or indicating device, so that the device may be used either with or without the head, and when the head is removed will function in the usual manner without adjustment or delay.

35 Another object is to produce a removable head which is completely sealed against the entrance of dust and moisture.

40 A further object of the invention is to produce a control head embodying a contact device of small mass and inertia, so that it will function quickly, accurately and positively, thereby insuring proper response of the parts to be controlled; and to provide self-contained damping means for this device.

45 50 Other objects will appear from the specification when read in conjunction with the accompanying drawings, in which:—

55 Figure 1 is a top plan view of one form of removable control head as it appears when in position on a magnetic compass;

Fig. 2 is a vertical sectional view on line II—II of Fig. 1;

Fig. 3 is a detail sectional view of the contact lifting magnet structure shown in Fig. 2;

Fig. 4 is a sectional view of the contact arm; 5

Fig. 5 is a detail sectional view showing one manner of attaching the magnetic coupling element and contact arm together; and

Fig. 6 is a diagrammatic view of one form of circuit for controlling the lifting magnet. 10

The control attachment to which this invention relates is applicable to various form of indicating devices, but for the sake of illustration it has been shown as applied to a magnetic compass. It will be understood, however, that it may be applied to a gyroscopic compass or to other indicating instruments which are intended to control an electric contact device without the imposition of any appreciable load upon the indicator. 15

In the drawings, the reference character A has 20 been used to designate generally a magnetic compass of the type adopted as standard by the U. S. Navy, while the reference character B has been used to indicate the removable control head to which this invention relates. 25

The compass A comprises a body 7 weighted at its lower portion, as indicated at 8. The body 7 is mounted to oscillate about a geometrical point with the usual gimbals comprising the knife edge trunnions 9, which engage seats provided for 30 them in gimbal ring 11, and the knife edge trunnions 12, which engage seats provided for them in the fixed supporting ring 13.

The chamber 14 within the compass contains the usual damping liquid which is confined by the 35 cover glass 15. This glass is sealed by a gasket 16, and it and the gasket are retained by the ring 17 which is fastened in place by screws 18, as shown.

40 Mounted at the center of the housing 7 is an upstanding pin 19 which carries at its top the pivot 21, the tip of the pivot being coincident with the point about which the compass tilts. Coacting with the pivot 21 is a conical bearing formed in a screw 22. This is threaded into a sleeve 45 which extends axially through the hollow float 23.

The purpose of the float is to sustain the compass card and the needles and thus reduce the load on the pivot 21. There are four tubes 24 which contain the magnetic needles used to give 50 the compass its directional characteristic. Of the four of these shown, two are longer than the other two and pass through the hollow float 23. The shorter two are substantially tangent to the sides of the float, all four needle tubes being in 55

mutual parallel relation with one another. It will be understood that the tubes make tight joints with the walls of the float so that the float is liquid tight.

5 Supported on the needle tubes 24 by means of brackets 25 is the annular compass card 26, bearing any desired indicia. Familiar markings have been sketched in Fig. 1.

The invention can be applied without modifying 10 the compass at all, but I prefer to add to the compass one additional bar magnet which is parallel with the tubes 24 and which is mounted on the top of the float 23 so as to be as near as possible to the cover glass 15. This magnet appears at 27. Its north seeking end is presented 15 in the same direction as the north seeking ends of the needles in the tubes 24, and it may be regarded merely as an auxiliary magnet acting in concert with the regular needles. From another 20 point of view, it may be regarded as a means for creating a magnetic field attached to any indicating device, whether that indicating device be magnetic in its characteristics, or not.

The control head designated B comprises an 25 annular casing 28, including a depending flange portion 10 adapted to fit over the top of the compass A. The inside of this flange is of greater diameter than the top of the compass in order to facilitate attachment and removal of the head. 30 In the clearance provided between the vertical wall of the top of the compass and the inside of flange 10, are two spaced lugs or pads 29 and 30, disposed approximately 120° apart.

The ring 10 also carries on one side, opposed 35 to the pads 29 and 30, a spring-pressed lug 40 working in an aperture 50, and biased inwardly by a spring 60 secured at both ends to the flange 10 and carrying centrally thereof the lug 40. The lower face of lug 40 is beveled to facilitate engagement of the head with the compass when 40 the head is lowered into position. It will be seen that the head B may be rotated freely with respect to the top of the compass, but that spring 60 forcing lug 40 against the compass casing will 45 oppose slight frictional engagement to the lifting of the head from the compass.

Secured to the casing 28 is a ring 29, held in place by screws 31 and including a bottom glass 32 cemented to it in water-tight relation. The 50 glass 32 preferably carries on its top side and at the periphery thereof, an etched azimuth circle or an azimuth circle carried by an additional ring, whereby a course may be set. As shown in the drawings, this azimuth circle is indicated at 33.

55 In the center of the glass 32 is a ring 34 threaded interiorly to carry a disc or anvil 35 for supporting the spindle of the contact arm in its lowered position and acting as a stop therefor. The ring 34 is spun into the glass in water-tight 60 relation thereto and the disc 35 may be adjusted up and down, as conditions may require.

The ring 29 has an upstanding flange 36 extending therearound and fitting within the casing 28, and adapted to support a contact ring 37. 65 This ring is composed of insulating material, such as phenolic condensation product, and has embedded in it a plurality of contact segments 38, 38a. The outer surface of the ring 37 contains a groove 43 adapted to house an electric conductor 70 80, which completes the circuits for the contacts carried in the ring.

Above the contact ring 37 is an insulating ring 39 engaging the bottom side of a cover glass 41. The space between the top of casing 28 and the 75 top of this glass is preferably sealed by a rubber

washer 42 fitting between the glass and a flange on the casing. The rubber ring 39 is of greater axial extent than the space in which it fits, so that when screws 31 are tightened, the ring 39 is compressed and holds the parts in water-tight 5 rigid relation.

The cover glass 41 is perforated in the center to receive the contact arm lifting magnet structure, including a housing 44, flanged to receive a sealing washer 45. The downwardly extending 10 end of the housing is rolled over a metal washer 46 to produce water-tight sealing engagement between the housing and glass 41.

Mounted within the housing 44 is a lifting magnet structure supported by a plurality of screws 15 47 and comprising a magnetizable shell or casing 48 open at the bottom, and containing a solenoid 49 made up of a very large number of turns of fine wire. This solenoid is carried on a central bearing or guide in the form of a tube 51 20 of non-magnetic material, such as brass, from which the wires 49 are insulated by an insulating tube 52. Discs 53 of insulating material complete the separation of the wires 49 from the magnetic structure of the magnet, while the 25 bottom end of housing 48 is closed by a magnetizable disc 54.

The top of housing 44 is closed by a cap 55 of non-magnetic material secured thereon by screws 56 and separated from the housing proper 30 by a sealing ring 57. This cap contains a chamber 58 within which the contact arm spindle can move upwardly when the solenoid is energized. Accordingly, the shell 48 has permanently secured to it in closely-fitting relation a flanged 35 tube 59 of magnetizable material. Below the tube 59 and slidable within the space inside of tube 51, is a magnetizable armature tube 61 permanently secured by a press fit to a non-magnetic sleeve 62 which extends throughout the 40 length of the solenoid and is freely slidable within the tube 59.

The armature 61 also carries around its top face a washer 63 of non-magnetic material, designed to prevent armature 61 and tube 59 from 45 coming into contact and thus preventing the residual magnetism in these elements from causing them to stick together when the armature is lifted by energization of the solenoid.

Fixedly mounted within the non-magnetic 50 tube 62 are two bushings 64 and 65 of insulating non-magnetic material, such as ivory, agate or other suitable bearing jewel material, and acting as bearings for a contact arm spindle 66. The spindle 66 is capable of shifting in the bushings 55 64 and 65, but its upward movement is dependent on movement of sleeve 62 and armature 61 when the solenoid 49 is energized. The top end of spindle 66 is threaded to receive a rubber nut 67 which absorbs the shock when the tube 62 rises 60 and hits it, and at the same time makes it possible to adjust the contact arm accurately with an adjustment which does not jar loose.

The lower end of spindle 66 carries a head 68 of non-magnetic material through which the 65 spindle passes, as shown in Fig. 5. The head 68 contains two aligned apertures for the reception of magnetic coupling magnets 69, which are driven tightly therein in alignment with each other and disposed at right angles to the axis of 70 contact arm 71. The contact arm is preferably secured to the head by heading down, as shown in Fig. 5. This contact arm may very well be made from a light metal, such as aluminum, and is centrally ribbed at 72 to make it stiff. This 75

arm carries at its extremities electric contact buttons 73 and 74 composed of electrically conducting metal having a high melting point and low vapor pressure and non-corrosive, such for example as platinum iridium. These buttons cooperate with the contacts carried by insulating ring 37.

When the solenoid 49 is energized, armature 61 is drawn upwardly within the tube 51, carrying 10 with it tube 62, spindle 66, and contact arm 71 and bringing the contact buttons 73 and 74 into engagement with contacts 38^a and 38, respectively, thereby limiting this upward movement. When the solenoid is deenergized, the contact 15 arm drops by gravity until the lower pointed end of spindle 66 engages the adjustable anvil 35, and its downward movement is cushioned by the damping action of chamber 89 as the air is sucked into it through the restricted passage 20 between tubes 62 and 59.

The configuration of contact arm 71 includes a slight upward bow, so that when it is drawn upwardly it has a slight spring and when disengaged, its resiliency facilitates quick disengagement between the buttons 73 and 74 and the contacts in ring 37.

Current is supplied to the solenoid 49 through two conductors 75 and 76, which pass through an opening 77 in casing 48 and the conductors 30 are insulated therefrom by a tube of insulation 78, the free ends of which are split and secured to the solenoid 49 at 79. The conductors 75 and 76 pass through an extension of insulating tube 78 and thence join the conductors leading to contacts 38, all of them being carried in a flat flexible woven cable 82 which enters the head of the casing through a water-tight opening 83, sealed by cement. Secured to this head adjacent the cable 82 is a flat curved support 84 which 35 prevents the conductors within cable 82 from being broken by their bending abruptly over the edge of the casing, and this support as well as the cable are held in place by a clamp 50. This flat cable solves the difficult problem of bringing 40 wires to the head without restricting the movement of the compass in its gimbals. Inasmuch as the cable 82 imposes a weight upon the compass head where it enters, and this weight unbalances the compass, this effect is overcome by 45 mounting on the head diametrically across from the cable a load counterbalancing weight 85, suitably secured thereto as by screws 86.

The circuits involved in this apparatus will be clear from an examination of Fig. 6, wherein the 50 conductors 75 and 76 are indicated as being connected to the solenoid 49 and controlled by a circuit controlling disc 87. As illustrated, the circuit controller 87 comprises a rotatable disc of insulation containing conducting segments 91 connected together by a wire 92. Two brushes 93 contact with the periphery of the disc and in the position shown complete the circuit of conductor 76. When the disc rotates to disconnect the brushes from the segments, this circuit is 55 open.

Connected to the contacts 38 are leads 70. Conductor 76 leading from one terminal of the source of current is connected to segment 38^a by wire 80. The wires 70 connected to contacts 70 38 are also connected to the other terminal of the source by operating circuits, not shown. Inasmuch as the circuits controlled by contacts 38 and 38^a in insulating ring 37 are not essential to an understanding of this invention, it 75 will suffice to state that when conductors 75

and 76 are connected to a suitable source of current by closing switch 88 and rotating circuit controller 87, the solenoid 49 will be energized to lift the contact arm, while upon further rotation of circuit controller 87, this circuit will be broken. 5

When the control head B is placed in position on the compass, as shown in Figs. 1 and 2, the magnets 69 swing into the magnetic stream of the compass, thereby making them parallel 10 to the needles and tubes 24. Inasmuch as the needles of the compass assume a north and south position, the contact arm 71 will be in an east and west position, and as shown will be in proximity to the contacts 38 and 38^a. 15

Each time that conductors 75 and 76 are energized, the solenoid 49 is energized and lifts the contact arm 71 to complete a circuit through the contacts, with which the arm 71 is in alignment. When this circuit is broken, or the circuit 20 established in any conductor 70, the contact arm will drop and will realign itself with the compass, due to the magnetic attraction between coupling magnets 69 and the magnet 27 carried by the compass bowl. 25

Chamber 89 acts as an air damping chamber from which the air is forced out along the clearance between tubes 62 and 59. This does not appreciably slow up the lift of the armature due to the strong magnetic pull, but on the 30 drop of the armature air must be sucked back into the chamber and a decided slowing up of the "drop" occurs so that the spindle and pivot 66 is "eased" back onto the anvil 35 without "bounce". The spindle 66 is freely movable inside of armature tube 61 so that the weight of the armature is not carried by the contact arm. This materially reduces the inertia of the contact arm and causes it to operate quickly and positively. 35

The working parts of the circuit controlling device are completely sealed between two sheets of glass, so that they are fully protected against dust and moisture and the slight heat developed in the solenoid 49 is sufficient to counteract the 40 collection of moisture within the contact arm chamber. The azimuth circle carried by bottom glass 32 enables the operator to set a course by turning the head until the desired course appears above the lubber line of the compass. 45 When this course has been established, the circuit controller will operate to maintain it. 50

It will be clear that the control head has no mechanical connection with the movable indicating member and may, therefore, be removed 55 without disturbing the operation of the indicating member. The indicator may be used either with or without the control head and the change from one use to the other may be made quickly without the use of tools and without 60 any adjustment of the parts other than to properly orientate the control head when it is applied.

Although the control head has been illustrated and described as applied to a magnetic compass, 65 it is obvious that it is capable of use in connection with any indicating device of this general character, where a rotatable indicating member is capable of having a magnetic coupling element attached to it. Accordingly, no limitations 70 are implied other than those expressly stated in the claims.

What is claimed is:

1. A removable control head for indicating instruments, comprising a pair of spaced parallel 75

- transparent plates mounted in watertight relation to an enclosing ring; a plurality of electric contacts mounted concentrically within the space between said plates; a rotatable contact arm adapted for cooperation with said contacts; and an electromagnet mounted between said plates and adapted to lift said contact arm into engagement with said contacts.
5. A removable control head for indicating instruments, comprising an enclosed watertight chamber made up of a pair of spaced transparent plates mounted in a supporting ring; a plurality of electric contacts mounted concentrically within the space between said plates; a rotatable contact arm adapted for cooperation with said contacts; an electromagnet for lifting said contact arm into contact with said contacts; and means for damping the movements of said arm.
10. 6. In a control head for indicating instruments, a plurality of concentric contacts; a rotatable contact arm adapted for selective cooperation with said contacts; a spindle secured to said arm; an armature rotatably but non-slidably mounted on said spindle; and a magnet for lifting said armature to bring said arm into cooperative relation with said contacts.
15. 7. In a control head for indicating instruments, a casing; a contact ring carried by and within said casing; a contact arm mounted in said casing for rotation with respect to said contact ring and capable of being lifted into contact with it; a solenoid having a movable core; means for securing said core to said arm but permitting relative rotational movement between them; means for energizing the solenoid to bring the contact arm into engagement with the contact ring; and means for damping the movement of said core and arm, when the solenoid is deenergized and the arm disengages the ring.
20. 8. In a control head for indicating instruments, a contact ring; a contact arm rotatably mounted with respect to said ring and capable of movement into and out of engagement with said ring; a magnet for lifting said arm; means comprising an enclosing ring and a pair of spaced parallel glass plates secured to said ring for enclosing said contacts, said arm and said magnet; and means comprising a fixed pivot for said arm secured in the bottom one of said plates for adjusting the lowered position of said arm with respect to said ring.
25. 9. In a control head for indicating instruments, a lifting magnet comprising a solenoid; a magnetizable core within said solenoid, said core comprising fixed and movable portions; a non-magnetic member separating said portions and preventing contact between said portions when the movable portion is brought toward the fixed portion by energization of the solenoid; a fixed contact ring; a contact arm free to rotate but secured against longitudinal movement with respect to the movable portion of said core and capable of engagement with said ring; and means for energizing said solenoid to lift said arm into contact with said ring.
30. 10. In a control head for indicating instruments, a contact head for indicating instruments, a casing comprising two transparent plates held in spaced relation by an enclosing ring to form a protective casing; a solenoid carried by one of said plates; a fixed core in said solenoid; a movable core in said solenoid; means for imparting to said movable core reciprocatory movement at unequal speeds respectively toward and away from the fixed core as the solenoid is energized and deenergized; a contact ring in said casing; a contact arm carried by and rotatable in said movable core but reciprocable only in concert with said movable core; magnetic coupling means carried by said arm in said casing; and means for energizing said solenoid to lift said arm into contact with said ring.
35. 11. In a closed control head for indicators, a contact ring; a contact arm cooperating with said ring; a solenoid for lifting said arm; a fixed core in said solenoid; a movable core loosely mounted for reciprocatory movement toward and away from said fixed core in response to energization and deenergization of said solenoid; means within said solenoid cooperating with said movable core to damp the downward movement of said core; means for rotatably securing said contact arm to said movable core, said means including a spindle secured at its lower end to said arm at right angles thereto, and having a rubber nut at its upper end above said fixed core; and means for energizing said solenoid to lift said contact arm into engagement with said contact ring, and then deenergizing said solenoid to permit said arm to drop.
40. 12. In a control head for indicating instruments, a casing; a contact ring carried by said casing; a rotatable contact arm capable of movement into and out of engagement with said ring; a lifting magnet for said arm, said magnet including a movable core; a spindle fixed to said arm but arranged to move upwardly with said core when said magnet is energized; and means comprising an air dash-pot within said magnet for damping the downward movement of the core, spindle and arm when the magnet is de-energized.
45. 13. In a removable control head for indicating instruments, a casing; a contact ring carried by said casing; a contact arm cooperating with said ring; a movable core portion rotatably secured to said arm; and a lifting magnet for said movable core portion, said magnet comprising a solenoid having a fixed core portion spaced from said movable portion to form a damping chamber with said movable portion and said solenoid when the movable portion is in motion.
50. 14. In a removable control head for magnetic compasses, comprising a pair of spaced transparent plates mounted in a ring to form a protective casing; a plurality of electric contacts mounted concentrically within the space between said plates; a rotatable contact arm adapted for cooperation with said contacts; a magnet carried by said contact arm; an electromagnet for lifting said magnet and said arm to bring said contact arm into contact with said contacts; and means for damping the downward movements of said arm and magnet.
55. 15. In a control head for indicating instruments, a casing comprising two transparent plates held in spaced relation by an enclosing ring to form a protective casing; a solenoid carried by one of said plates; a fixed core in said solenoid; a movable core in said solenoid; means for imparting to said movable core reciprocatory movement at unequal speeds respectively toward and away from the fixed core as the solenoid is energized and deenergized; a contact ring in said casing; a contact arm carried by and rotatable in said movable core but reciprocable only in concert with said movable core; magnetic coupling means carried by said arm in said casing; and means for energizing said solenoid to lift said arm into contact with said ring.
60. 16. In a control head for indicating instruments, a contact ring; a contact arm cooperating with said ring; a solenoid for lifting said arm; a fixed core in said solenoid; a movable core loosely mounted for reciprocatory movement toward and away from said fixed core in response to energization and deenergization of said solenoid; means within said solenoid cooperating with said movable core to damp the downward movement of said core; means for rotatably securing said contact arm to said movable core, said means including a spindle secured at its lower end to said arm at right angles thereto, and having a rubber nut at its upper end above said fixed core; and means for energizing said solenoid to lift said contact arm into engagement with said contact ring, and then deenergizing said solenoid to permit said arm to drop.
65. 17. In a control head for indicating instruments, a contact ring; a contact arm cooperating with said ring; a solenoid for lifting said arm; a fixed core in said solenoid; a movable core loosely mounted for reciprocatory movement toward and away from said fixed core in response to energization and deenergization of said solenoid; means within said solenoid cooperating with said movable core to damp the downward movement of said core; means for rotatably securing said contact arm to said movable core, said means including a spindle secured at its lower end to said arm at right angles thereto, and having a rubber nut at its upper end above said fixed core; and means for energizing said solenoid to lift said contact arm into engagement with said contact ring, and then deenergizing said solenoid to permit said arm to drop.

BRADFORD B. HOLMES.
